UNITED STATES PATENT OFFICE.

NOAH FERGUSON, OF LAPAZ, INDIANA.

RAILWAY-TIE TAMPER.

SPECIFICATION forming part of Letters Patent No. 759,359, dated May 10, 1904.

Application filed August 15, 1903. Serial No. 169,648. (No model.)

To all whom it may concern:

Be it known that I, NOAH FERGUSON, a citizen of the United States, residing at Lapaz, in the county of Marshall and State of Indiana, have 5 invented a new and useful Rail-Tie Tamper, of which the following is a specification.

My invention is an improvement in tampers and is designed especially for tamping ties on a railroad.

10 The object of the invention is to devise a tool of this character which will save time and labor. Heretofore plain bars have been used for tamping. A plain bar will only carry a limited amount of sand, loose dirt, or gravel 15 under a tie and will pull more or less out.

The object of my invention is gained by constructing a tool which will carry more dirt or gravel under a tie than will be carried by a plain bar and will not pull as much out from under 20 the tie in proportion to what it takes in, thereby enabling the workman to tamp a tie with fewer strokes than with a bar of the usual construction.

My invention consists of the novel features 25 of construction and combination of parts hereinafter described, particularly pointed out in the claims, and shown in the accompanying drawings, in which—

Figure 1 is a perspective view showing the 30 application of my device. Fig. 2 is a plan view, the central handle portion being broken. Fig. 3 is a side elevation. Fig. 4 is a face view of the end shown on the right in Fig. 2. Fig. 5 is a perspective view.

35 My tamping-tool consists of a bar A, having the central offset portion A', the bar terminating at each end in a rectangular body portion B and B'. Parallel grooves C are formed on opposite faces of these body portions and extend from the end of the body portion to a point adjacent the handle, the grooves having flat bottoms and vertical sides. V-shaped notches D are cut into the outer ends of the grooves, the ends of the body portions between the grooves presenting blunt striking-surfaces E, adapted to pack the dirt and gravel carried under the tie by the tool. The grooves of the end B are approximately one-half an inch deeper than those of the end

B', the former-mentioned end being used when 50 a considerable amount of earth is to be packed under a tie.

The offset A' of the handle portion permits the tamper to be used in practically a horizontal position, as when tamping under the 55 center of a tie, without bringing the hands of the user in contact with the ground, thus obviating one of the main objections to a straight bar.

It will be obvious that the grooves will carry 60 considerable dirt, sand, or gravel under the tie and that the amount carried under one stroke will be packed by the blunt ends E on the succeeding stroke. The notches D prevent the reduced portion formed by the 65 grooves from striking and tearing the material previously packed. They also aid in guiding gravel and sand into the grooves C.

Having thus fully described my invention, what I claim as new, and desire to secure by 70 Letters Patent, is—

1. A device of the kind described comprising a central handle portion terminating at each end in a rectangular body portion, said body portions being longitudinally grooved 75 from their outer ends to a line adjacent the handle portion, and having notches formed in their outer ends in alinement with said grooves.

2. A device of the kind described comprising a central handle portion offset midway its ends, said handle portion carrying rectangular, longitudinally-grooved body portions at each end, the outer ends of said body portions having V-shaped notches therein in alinement 85 with the grooves.

3. A device of the kind described comprising a handle portion offset midway its ends, and rectangular body portions formed integral with each end of the handle portion, said 90 body portions being longitudinally grooved on opposite faces, and notched at the ends in alinement with said grooves.

NOAH FERGUSON.

Witnesses:

ISAM RECTER,
EDWARD COOK.
